HUMIDIFYING DEVICE FOR INTERNAL COMBUSTION ENGINES

Filed April 21, 1938

UNITED STATES PATENT OFFICE

2,218,653

HUMIDIFYING DEVICE FOR INTERNAL COMBUSTION ENGINES

Edward Niethamer, Bay City, Mich.

Application April 21, 1938, Serial No. 203,283

3 Claims. (Cl. 123—25)

One of the prime objects of the invention is to design a simple, practical, and economical humidifying device by means of which steam and/or moist air can be supplied to the intake manifold 5 of the engine to provide a moist explosive mixture.

A further object is to provide a new and novel arrangement and combination of metal container associated with the exhaust pipe for generating 10 the steam drawn into the intake manifold.

A still further object is to provide a humidifying device which can be easily and quickly assembled and mounted, which requires no change fitting, or alteration in the engine or vehicle 15 body, and which can be mounted by unskilled labor.

A further object still is to provide means for easily and quickly draining the liquid from the receptacle.

With the above and other objects in view, the present invention consists in the combination and arrangement of parts, hereinafter more fully described, illustrated in the accompanying drawing, and more particularly pointed out in the appended claims, it being understood that changes 25 may be made in the form, size, proportion, and minor details of construction, without departing from the spirit, or sacrificing any of the advantages of the invention.

30 In the drawing:

Fig. 1 is a side elevation of an internal combustion engine showing my humidifying device in place thereon.

Fig. 2 is an enlarged part sectional view showing the valve connection to the exhaust manifold.

Fig. 3 is an enlarged side elevational view of the water container, exhaust pipe, etc.

Fig. 4 is a transverse sectional view taken on the line 4—4 of Fig. 3.

40 Fig. 5 is an enlarged fragmentary detail showing the drain cock.

Referring now to the drawing in which I have shown one embodiment of my invention, the numeral 8 indicates a conventional internal combustion engine provided with an exhaust pipe 9 as usual, a manifold 10 forms a part of the engine, and a pipe nipple 11 opens into said manifold and is connected to a valve section 12 for controlling the admission of moist air to the 45 manifold, a cylindrical shell 13 surrounds the valve 12, and an operating rod 14 is connected to said valve and leads to the vehicle instrument board 15 to facilitate manipulation thereof, all as shown and described in Patent #2,112,972 granted 50 to me under date of April 5, 1938.

The liquid container 16 is preferably formed as shown in Figs. 3 and 4 of the drawing, although it may be formed of any other shape desired, this container snugly fitting and partially embracing the surface of the exhaust pipe and being secured in position by means of flat sheet metal strips 17, the end sections of which are rounded and threaded to engage a clamp 18 which embraces the lower half of the exhaust pipe, nuts 19 serving to secure the parts in assembled relation. 5

The liquid container is formed to fit the curve or bend of the exhaust pipe, and a connection 20 is provided on the upper end thereof, a similar connection 21 being provided on the shell 13, and 15 a flexible hose member 22 connects the container with said shell.

I wish to direct particular attention to the fact that there are no additional openings in the liquid container with the exception of an overflow 20 23 provided as shown to indicate when the container is full.

Under certain conditions, it is desirable to drain the container from time to time; for instance, in cold weather when the vehicle is to be 25 idle for a considerable period of time, and I therefore, provide a drain cock 24 on the lower end section of the container. A spring pressure closure member 25 forms a part thereof, and a rod 26 is connected thereto and leads to the foot 30 board of the vehicle (not shown) so that it can be readily actuated by the driver by merely pressing on the end of the rod, the spring pressed closure member 25 springing back to original closed position as soon as the pressure is released. 35

In practise the hot exhaust gases from the engine quickly heat the liquid in the container so that humidity is supplied almost as soon as the engine is started, the valve 12 being manipulated to regulate the volume admitted. 40

It is important that no dirt, dust, or other foreign matter enter the liquid container, and it can be filled at any regular gas station in the same manner as is the radiator. This is accomplished by removing the hose 22 from the fitting 45 21 placing a funnel (not shown) in the end thereof and pouring the liquid through the hose, the overflow being provided to indicate when the receptacle is full.

The device can easily and readily be installed 50 with common tools and in a short space of time, and will enable the motorist to travel more miles per gallon of gasoline consumed, and thus effect a substantial saving in the operation of the automobile. 55

From the foregoing description, it will be obvious that I have designed and perfected a very simple, practical and economical humidifying device for internal combustion engines.

5. What I claim is:

1. In a humidifying device for internal combustion engines and comprising a valve mounted on and communicating with the intake manifold of the engine, a shell mounted on and surrounding said valve, an elongated, readily bendable, sheet metal liquid receptacle mounted lengthwise on the exhaust pipe of the engine and embracing same, flexible means establishing communication between said shell and the receptacle, straps for securing said receptacle in position, and an overflow port at the upper end of the receptacle to indicate when the receptacle is full.

2. A humidifying device for internal combustion engines comprising a valve mounted on and communicating with the intake manifold of the engine, a shell surrounding said valve, an elongated, sheet metal, liquid receptacle mounted

lengthwise on the exhaust pipe of the engine and shaped to fit the longitudinal curvature thereof, a flexible pipe establishing communication between said shell and the receptacle, an overflow port at the upper end of the receptacle, and a spring retracted, foot actuated drain cock on the lower end of the receptacle.

3. The combination with an automotive vehicle including an engine, a valve mounted on and communicating with the intake manifold, a shell surrounding said valve, an elongated, sheet metal, liquid receptacle mounted lengthwise on and closely fitting the engine exhaust pipe and communicating with said shell, a drain cock mounted on the lower end of the receptacle and provided with a spring retracted closure member, a rod connected to the closure member and leading to the foot board of the vehicle, and adapted to be actuated to drain the receptacle, and means for holding the receptacle in set position.

EDWARD NIETHAMER.
